UNITED STATES PATENT OFFICE

FREDERICK T. RUSSELL, OF UTICA, NEW YORK, ASSIGNOR, BY MESNE ASSIGNMENTS, TO FOX COMPANY, OF PHILADELPHIA, PENNSYLVANIA, A CORPORATION OF PENNSYLVANIA

TOY GUN OF THE REPEATER TYPE

Application filed April 11, 1930. Serial No. 443,278.

This invention relates to toy guns, and more particularly to those guns in which a relatively light ball is projected out of the barrel of the gun and toward a mark by 5 the impact of a spring-impelled plunger.

The object of the present invention is to provide a toy gun which in outward appearance closely resembles a real rifle, that is to say, a firearm, although the frame, barrel 10 and trigger-guard are stamped and formed of a single integral piece of sheet metal.

A further object of my invention is to provide a toy rifle in which one or a plurality of balls may be inserted through an 15 opening in the wall of the barrel into a chamber provided in the barrel and retained in said chamber until the gun is cocked and to provide a structure wherein, when the gun is cocked, one ball at a time and one 20 only may be caused to roll forwardly gravitationally into a recess wherein it is in alignment with and in advance of a strike-pin, whereby the impact of the said pin on the said ball upon the release of the spring- 25 impelled plunger projects the ball out of said chamber and through the barrel in the direction of the mark or target aimed at.

A further object of my invention is to provide a simple means for rigidly securing 30 the impact block within the barrel against displacement under the repeated and severe blows imposed thereon by the spring-impelled plunger.

A further object of my invention is to 35 provide a simple and efficient means for maintaining the major portion of the plunger rod in substantial alignment with the axis of the barrel by providing the rear end of the rod with sharply bent portions which 40 cooperate with the stationary abutment at the rear end of the propulsion spring, and with a slot through a side of the frame in which one of said portions extends laterally 45 and in which it slides in its travel with the plunger.

A further object of my invention is to 50 make a faithful miniature model of a real rifle, of few and simple parts, which may be constructed and assembled at a low cost,

said parts being not easily broken, or displaced or subjected to any particular wear.

Other objects of this invention will appear in the specification and claims below.

Referring to the drawings forming a part 55 of this specification and in which the same reference characters are employed throughout the various views to designate the same parts,

Fig. 1 is a side elevational view, partly in 60 section, of a toy rifle embodying my invention and with the rear end of the stock, which may be of ordinary design and construction, broken away, and with the operative parts of the gun shown in the cocked 65 position,

Fig. 2 is a view similar to Fig. 1, but showing the relative positions of the parts immediately after the gun has been fired.

Figs. 3, 4, 5, 6, 7, 8 and 9 are vertical 70 transverse sections of Fig. 1, taken on the lines 3—3, 4—4, 5—5, 6—6, 7—7, 8—8 and 9—9 respectively, the Figures 4 to 9, inclusive, being on a larger scale than that of Figs. 1, 2 and 3.

Fig. 10 is a perspective view showing the frame, trigger-guard and the barrel made of a single piece of sheet metal, the forward 75 end of the barrel being broken away, however, for the sake of clearness in illustrating the invention.

Briefly, the barrel 1, frame 2 and the trigger-guard 3 are made from a blank sheet metal stamping from which flanges 2^a, 2^a of the frame are struck or turned up around the side walls 2^b, 2^b of the frame 2 and the flanges 3^a, 3^a are struck up from the sides of the trigger-guard 3, said flanges being of such a height that when that part of the blank which forms the top of the finished frame 2 is bent into substantially semicylindrical form and the portions, of the blank which form the barrel are also bent into cylindrical form, with the side walls 2^b of the frame parallel, the flanges 2^a, 2^a, projecting toward each other from opposite sides, will squarely abut against each other and the flanges 3^a, 3^a will also respectively abut against each other to close the bottom of 80 the frame 2 and to provide a sturdy trigger- 85

guard of substantially rectangular shape in cross-section. After having been bent into the shape shown in Figs. 3 and 10, it is then only necessary to spot-weld the flanges 2^a 5 together as at the spot-weld 4 and to solder or spot-weld the abutting edges on the underside of the barrel, preferably by spot-weld 5 at the point where the barrel is provided with a circumferential or circular indentation 10 6 which forms a rigid integral shoulder 7 on the inside of the barrel against which the forward end of the impact block 8 firmly abuts, as will be referred to again below.

The portion of the barrel to the rear of 15 the impact block 8 and between it and the forward end of the stationary rear abutment 9, provides a chamber 10, in which is mounted a piston or plunger 11 having a plunger rod 12 rigidly attached thereto the major 20 portion 12^a of which is straight and extends into the rear abutment 9 when the piston or plunger 11 is in engagement with the rear face of the impact block 8. Surrounding the straight portion 12^a of the plunger rod 25 12, is a coiled compression spring 13, the rear end of which is seated against the forward end of the rear stationary abutment 9 and the forward end of which surrounds and fits a projection 11^a forming the rear end of the 30 piston or plunger 11.

The rear abutment 9 preferably comprises a cylindrical rod of wood provided with a relatively deep slot or channel 9^a extending the full length of the rod, and radially disposed. The plunger rod 12 slidingly fits 35 between the vertical sides of the slot 9^a. The forward end of the abutment 9 preferably fits into the rear end of the cylindrical barrel 1 and the rear end of the abutment 9 is 40 seated squarely against the forward end of the stock 14 which telescopically fits into the open rear end of the frame 1 and is rigidly secured therein by the bolts or rivets 15—15.

The forward end of the stock 14 is preferably 45 provided with a staple or any other suitable flat projection 16, which will fit into the slot 9^a and will hold the rear end of the abutment 9 firmly against the inside of the top of the frame and will maintain the slot 50 9^a vertical and opening downwardly.

The rear end of the straight portion 12^a of the plunger rod terminates in a substantially vertical portion 12^b extending out of the slot to a point below the abutment 9 and 55 said section 12^b terminates in another straight section 12^c extending horizontally and normal to the plane of the side 2^b of the frame 2, and out through a slot 17 in the said side 2^b. Said slot 17 extends longitudinally 60 parallel to the axis of the barrel 2, but its lower edge forms a support or rest on which the said horizontal portion or extension 12^c may freely slide. The outer end of the section 12^c terminates in a handle section 12^d 65 provided with a knob or grip 18 by means

of which one may draw backwardly or rearwardly on the grip 18 and retract the plunger 11 against the tension of the coiled spring 13.

Within the frame 2 is a trigger 19 mounted to turn on a pivot pin 20, said trigger being provided with a detent 21 which, under the expansive tension of the trigger spring 22, normally lies against the cylindrical surface of the abutment 9 in the path 70 of the movement of the portion 12^c of the plunger rod as it nears the rearward limit of its motion. When the grip 18 is drawn rearwardly, the transverse horizontal section or portion 12^c of the plunger rod engages the forward beveled edge of the trigger 19, depresses it until the section 12^c passes over the detent 21 whereupon the spring 22 forces the detent upwardly so as to retain the plunger rod, and plunger attached thereto, 75 in their rearmost position against the tension of the spring 13.

To fire the gun it is only necessary to pull the trigger 19, thus releasing the plunger rod from the detent 21, whereupon the spring 13 impels the piston or plunger 11 and the plunger rod 12 attached thereto forwardly until the plunger engages the rear face of the impact block 8.

It may here be noted that the flanges 2^a, 2^b of the frame are notched between the points where the trigger guard 3 joins the frame to provide a slot 23 to guide the projecting end of the trigger in a straight path. The forward end of the stock 14 is preferably provided with a recess 24 in which is seated the trigger spring 22, the forward end of the trigger spring surrounding a suitable projection 19^a on the trigger. Any forward movement of the trigger substantially beyond the point shown in Figs. 1 and 2 is prevented by the engagement of the detent 21 with the cylindrical surface of the wooden abutment 9.

Referring to Fig. 3, it will be observed that substantially all of the trigger within the frame is offset from the middle of the frame to a point approximately midway between the ends of the horizontal section 12^c of the plunger rod, and that substantially only the lower end of the trigger, which extends through the slot 23, is vertically below the axis of the barrel or midway between the sides 2^a of the trigger-guard 3.

The impact block 8 is preferably made of hard wood, is firmly seated against a shoulder 7, and is preferably retained in position by indentations 25 in the metal of the barrel 1 into the wooden impact block 8, as is clearly shown in Fig. 6. The impact block is also preferably provided with a hole 26 through which the strike-pin 27 is free to move as will be described below.

In advance of the indentation 6 and tightly fitting within the barrel 1 is a ball re-

ceiver 28, which preferably comprises a cylindrical wooden plug or body, provided in its upper cylindrical surface or side with a longitudinally extending groove or channel 29 of a depth substantially greater than the diameter of the balls 30 to be placed therein so that the balls will roll freely gravitationally within said groove 29 when the gun is tilted up and down. The forward end of said groove or runway 29 terminates in a recess or chamber 31 of a size sufficient to hold one and only one of the balls or projectiles 30. Below said groove or runway 29 is a longitudinally extending hole 32 in which slidably fits the strike-pin 27, and leading rearwardly into a larger cylindrical hole forming a chamber 33. That part of said strike-pin 27 which lies in said chamber 33 is provided with a flange 34 or shoulder 34 between which and the forward end of said chamber 33 a light coiled spring 35 surrounding said strike-pin is held under compression. The tension of said spring 35 is such as to normally impel the strike-pin 27 rearwardly to hold the flange or shoulder 34 against a metal washer or head 36 secured to the rear end of said body 28 and provided with a hole 37 in alignment with the hole 32 in the ball container and the hole 26 in the impact block 8 and in which the rear end of said strike-pin 27 freely slides. The other end of the ball receiver 28 is also preferably provided with a metal washer or head 38 provided with an opening 39 slightly larger than a ball 30 through which a ball or projectile 30 may drive under the impact of the strike-pin. Said body 28 is preferably provided with a groove 40 near the forward end thereof in which there is tightly wrapped and secured a light spring wire 41, having a free end 41^a brought forwardly over the edge of the metal head 38 and bent down against the outer surface of said head 38 and across the opening 39 to form a resilient ball retainer operative to prevent the ball from rolling gravitationally through the opening 39 when it is seated in the recess 31. (See Fig. 9.)

The ball receiver 28 is preferably securely held within the barrel against rotative movement about its axis by indentations 42 (see Fig. 7) through the metal of the barrel and into the outer cylindrical surface of the wooden body or block 28. In this manner the strike-pin 27 is securely maintained in alignment with the hole 26 through the impact block 8. The metal washer or head 38 on the forward end of the ball container 28 is preferably of slightly smaller diameter than the interior of the bore of the barrel 1 in order to permit of the passage of the light wire thereover and across the opening 39 therein. (See Fig. 9.) The free end 41^a of the wire lies across the opening or

hole 38, forming substantially a chord subtending a small arc of said opening 39 and making the larger clear passage through the hole less than the diameter of a ball.

At the rear end of said groove 29, through the top of the barrel, is a circular hole or opening 43 for the insertion of a ball into the runway or groove 29. One ball may be placed therein or a plurality of balls sufficient to fill the full length of the groove 29 with one lying on the strike-pin 27, may be inserted, as indicated in Fig. 2.

When the gun is "uncocked" the parts are in the position shown in Fig. 2 with the plunger 11 held tightly against the impact block 8 by the tension of the stiff propulsion spring 13. The strike-pin 27 is in its forward position with the light spring 35 compressed between the flange 34 and the end of the chamber 33, and both the forward end of the strike-pin 27 extending substantially through the recess or chamber 31, and operative to prevent the foremost ball of the series of balls from dropping to the bottom of said chamber or recess 31 into a position in substantial alinement with the strike-pin 27. To cock the gun, the operator draws rearwardly on the handle or grip 18, retracting the plunger 11 against the tension of said spring 13 until the horizontal portion 12^a of the plunger rod 12 passes to the rear of the detent 21 of the trigger 19. In so doing, the portion 12 of the rod slides smoothly on the lower edge of the slot 17 in the frame. Any rotational movement around the axis of the straight portion 12^a of the rod being prevented by the vertical bend or section 12^b and its substantial engagement with the vertical walls of the channel 9^a in the stationary rear abutment 9. As the plunger 11 moves rearwardly the strike-pin 27 moves rearwardly in contact therewith under the pressure of the light spring 35 until the shoulder or flange 34 engages the forward side of the metal washer or head 36 (as position shown in Fig. 1). In this position the forward end of the strike-pin 27 is substantially flush with the rear wall of the recess or chamber 31 and in so retracting the foremost ball 30 will fall to the bottom of the recess 31 (as shown in Fig. 1). But said ball, substantially filling the recess 31, is operative to prevent the ball immediately behind it from entering said chamber. The latter will be supported upon the lower ball out of the path of the strike-pin 27.

Upon the release of the plunger rod from the trigger 19, the plunger before reaching the impact block 8, strikes the rear end of the strike-pin 27 driving it forwardly at high speed against the ball 30 in the recess or chamber 31 forcing it over the light retaining spring wire 41^a, which offers substantially no resistance to the force of the

blow on the strike-pin from the plunger 11. The impact of the forward end of the strike-pin 27 against the ball is the impelling force which drives the ball 30 past the spring 41^a and out of the barrel in the direction of the mark or target aimed at.

For the purpose of enabling one to sight the gun at a given object or target, the forward end of the barrel may be provided with 10 a projection expressed outwardly from the body of the barrel to form a forward sight 44, and at the rear end of the frame 2 is preferably struck-up an alined rear sight 45 provided with a circular opening 45^a 15 therethrough through which the forward sight 44 may be readily seen and the gun aimed in the desired direction.

The gun constructed in the manner above described is very rigid, due to the reinforcement and strengthening of the sheet metal due to the shape of the frame and trigger-guard, and to the fact that the frame is rigidly secured to the forward end of the stock by the rivets 15 passing through the stock 25 and through the frame and headed over on the outside of the frame, to the tubular shape of the barrel, to the reinforcement thereto formed by the annular groove or indentation 5 and to the pivot pin 20 of the trigger, 30 the ends of which are headed over on the outside of the frame. Because of this strong construction it is unnecessary to unite the abutting edges of the barrel frame or trigger throughout the length of the abutting edges. It is sufficient to merely spot-weld 35 the edges together at one or two points as by the spot-welds 4 and 5 on the frame and on the underside of the barrel respectively.

Having thus described my invention, what 40 I claim and desire to protect by Letters Patent of the United States is:

1. In a toy gun, the combination of a frame and a barrel integral with each other and of sheet metal, said barrel being provided with a circumferential annular inwardly indented groove intermediate the ends of said barrel to form a rigid shoulder within the bore of said barrel, an impact block fitting said bore in the rear of and 50 seated against said shoulder, a spring-imelled, trigger-controlled impact plunger reciprocable within said barrel and in the rear of said impact block, the forward movement of which is limited by said impact block, a ball retainer fitting the bore of said barrel and fixedly positioned substantially against the forward shoulder provided by said circumferential groove, a longitudinally reciprocable strike-pin mounted in said ball retainer, and a light spring normally yieldingly holding said strike-pin in its rearmost position with its rear end projecting through said impact block into the path of the forward movement of said plunger.

2. In a toy gun, the combination of a

frame and a barrel integral with each other and of sheet metal, said barrel being provided with a circumferential annular inwardly indented groove intermediate the ends of said barrel to form a rigid shoulder within the bore of said barrel, an impact block fitting said bore in the rear of and seated against said shoulder, a spring-imelled, trigger-controlled impact plunger reciprocable within said barrel and in the rear of said impact block, the forward movement of which is limited by said impact block, a ball retainer fitting the bore of said barrel and fixedly positioned substantially against the forward shoulder provided by said circumferential groove, a longitudinally reciprocable strike-pin mounted in said ball retainer, and a light spring normally yieldingly holding said strike-pin in its rearmost position with its rear end projecting through said impact block into the path of the forward movement of said plunger, said ball retainer being provided with means to hold said ball in said retainer in alinement with the forward end of said strike-pin when said strike-pin is in its rearmost position.

3. In a toy gun, the combination of a frame and a barrel integral with each other and of sheet metal, said barrel being provided with a circumferential annular indented groove intermediate the ends of said barrel to form a rigid shoulder within the bore of said barrel, an impact block fitting said bore and seated against the rear side of said shoulder, a spring-imelled, trigger-controlled plunger, reciprocable within said barrel in the rear of said impact block, a propulsion spring operative to drive said plunger against said impact block, a ball retainer within said bore and fixedly positioned therein against the forward side of said shoulder, a longitudinally reciprocable strike-pin mounted in said ball retainer, and means normally yieldingly holding said strike-pin in its rearmost position with its rear end projecting through said impact block into the path of the movement of said plunger, said ball retainer being provided with means to hold a plurality of balls and with means to position the foremost ball in alinement with the forward end of said strike-pin when said strike-pin is moved to its rearmost position.

4. In a toy gun, the combination of a barrel and a frame integrally made of a single piece of sheet metal, said frame being provided with a slot through a side thereof and parallel to the axis of said barrel, a stationary spring abutment having a longitudinal channel therein, an impact plunger mounted in said barrel and provided with a plunger rod having a straight portion extending rearwardly substantially coaxial with the barrel into said channel and terminating in a portion extending at an angle

to said straight portion to a point outside of said channel and from which point another portion of said rod extends outwardly through said slot in said frame, and a grip 5 connected with said last-mentioned portion for retracting said plunger.

5. In a toy gun, the combination of a barrel and a frame integrally made of a single piece of sheet metal, said frame being 10 provided with a slot through a side thereof and parallel to the axis of said barrel, a stationary spring abutment having a longitudinal channel therein, an impact plunger mounted in said barrel and provided with 15 a plunger rod having a straight portion extending rearwardly substantially coaxial with the barrel into said channel and terminating in a portion extending at an angle to said straight portion to a point outside 20 of said channel and from which point another portion of said rod extends outwardly through said slot in said frame, a grip connected with said last-mentioned portion for retracting said plunger, and means in the 25 path of movement of said last-mentioned portion to engage said horizontal portion between said abutment and said slot in said frame when said plunger is near the rearward limit of its travel to releasably retain 30 the plunger and plunger rod retracted against the tension of said propulsion spring.

6. In a toy gun, the combination of a barrel, a frame having a longitudinal slot 35 through a side thereof parallel to the axis of said barrel, an impact plunger reciprocable in said barrel, a stationary spring abutment comprising a cylindrical wooden rod having its forward end fitting into the 40 rear end of said barrel and its rear end in said frame, said rod being provided with a longitudinal channel extending for substantially the full length thereof and having vertical parallel walls, and extending from 45 the surface of said rod substantially radially to and through the axis of said rod, means to prevent any movement of said abutment relative to said frame, a propulsion spring compressible between said plunger and said 50 stationary abutment, and a plunger rod extending straight rearwardly from said plunger through said propulsion spring into said channel in said stationary abutment when said plunger is at the limit of its forward movement, and having the end thereof bent at an angle to project out of said channel and thence extending outwardly through said slot in said frame whereby the rear end of said plunger rod is supported against any substantial movement except parallel to the axis of said plunger.

7. In a toy gun, the combination of a barrel, a frame having a longitudinal slot 60 through a side thereof parallel to the axis of said barrel, an impact plunger recipro-

cable in said barrel, a stationary spring abutment comprising a cylindrical wooden rod having its forward end fitting into the rear end of said barrel and its rear end in said frame, said rod being provided with a longitudinal channel extending for substantially the full length thereof and having vertical parallel walls, and extending from the surface of said rod substantially radially to and through the axis of said rod, means to prevent any movement of said abutment relative to said frame, a propulsion spring compressed between said plunger and said stationary abutment, a plunger rod extending straight rearwardly from said plunger through said propulsion spring into said channel in said stationary abutment when said plunger is at the limit of its forward movement, and having the end thereof bent at an angle to project out of said channel and thence extending outwardly through said slot in said frame whereby the rear end of said plunger rod is supported against any substantial movement except parallel to the axis of said plunger, and releasable means engaged by that portion of said plunger rod between said channel and said slot in the frame to hold said plunger and rod retracted against the tension of said propulsion spring.

8. In a toy gun, the combination with a barrel, an impact plunger reciprocable in said barrel between limits therein and an impact block rigidly mounted in said barrel to receive the impact of said plunger, of a projectile holder rigidly secured in said barrel in advance of said impact block and comprising a block provided with a longitudinal groove in the upper surface thereof to receive and support an aligned series of balls and provided with a recess at the forward end thereof below said channel into which a ball may fall from said channel, a strike-pin extending longitudinally through said impact block and through said projectile holder below said groove and longitudinally reciprocable through said recess in said projectile holder, a light spring normally tending to hold said strike-pin in its rearmost position with the rear end of said strike-pin in the path of movement of said plunger and the forward end of said strike-pin substantially in the rear wall of said recess in said projectile holder.

9. In a toy gun, the combination of a barrel and a frame stamped out of a single integral piece of sheet metal, the frame being provided with a slot through one side thereof parallel to the axis of said barrel, a stock fitting into the rear end of said frame and rigidly secured thereto, a stationary spring abutment comprising a cylindrical body having a longitudinally radially disposed channel, the forward end of said body fitting into the rear end of said barrel and the rear end

of said body abutting against said stock, a projection on said stock fitting between the walls of said channel to support the rear end of said body against the inside of the top of said frame and to prevent rotational movement of said body within said barrel, a compressed propulsion spring between said plunger and the forward end of said stationary abutment, a plunger rod having a straight portion extending rearwardly from said plunger, substantially axially of said barrel into said channel when said plunger is at the limit of its forward movement, and terminating in a portion extending at an angle to said straight portion outwardly to a point beyond said cylindrical surface of said abutment, said portion terminating in another portion extending horizontally outwardly through said slot in said frame, a grip connected with said last mentioned portion for retracting said rod and plunger together, and a trigger detent in the path of the movement of said horizontal portion of said plunger rod between said abutment and said slot in said frame to take over said horizontal portion near the rearward limit of its travel to hold said plunger retracted against the tension of said propulsion spring.

30 10. In a toy gun, the combination with a frame and a barrel made out of a single integral piece of sheet metal, a stock fitting into and rigidly secured to the rear end of said frame, an impact block in said barrel intermediate said frame and the forward end of said barrel, said frame being provided with a slot through one side thereof parallel to the axis of said barrel and said barrel being provided with a circumferential inwardly extending groove providing a rigid shoulder in the interior of said barrel against which said impact block is firmly seated against forward movement, a plunger reciprocable in said barrel between said impact block and said frame, a stationary spring abutment mounted in the upper part of said frame and fitted into the rear end of said barrel and provided with a channel in the underside thereof having parallel sides and extending through the axis of said barrel, a plunger rod unitary with said plunger provided with a straight major portion extending rearwardly from said plunger and entering said channel in said abutment, when said plunger is in engagement with said impact block, said straight portion of said plunger rod terminating in a short straight portion fitting between the walls of said channel and extending to a point outside of said channel and terminating in a portion extending therefrom outwardly through said slot in said frame, and a trigger provided with a detent for taking over said last-mentioned portion of said

plunger rod when the plunger has been retracted to its rearmost position.

11. In a toy gun, the combination with a frame and barrel made of a unitary piece of sheet metal, an impact block mounted within said barrel, said barrel being provided between said frame and the end of said barrel with a circumferential inwardly extending groove providing a shoulder in the interior of said barrel against which said impact block is permanently seated against forward movement, an impact plunger mounted to slide in said barrel and impinge against the rear surface of said impact block at the end of its forward movement, a ball receiver rigidly secured within said barrel adjacent and forward of said circumferential groove and comprising a cylindrical body provided in the surface thereof with a groove parallel to the axis of said body, for the reception of a plurality of aligned balls, said barrel being provided with an opening for the introduction of said balls into said groove at the rear end of said groove, the forward end of said groove terminating in a recess into which the foremost ball in said receiver may fall, a strike-pin mounted in said body parallel to the axis thereof and below said groove, resilient means normally holding said strike-pin in its rearmost position with its rear end projecting through said impact block into the path of said plunger, the forward end of said strike-pin in said position being substantially flush with the rear wall of said recess, the forward end of said ball receiver being provided with an opening in alignment with said ball in said recess and substantially in alignment with said strike-pin, and yielding means to retain said ball within said recess until said ball is impelled forwardly by said strike-pin past said resilient means by the impact of said plunger on said strike-pin.

12. In a toy gun, the combination of a frame, a barrel, an impact block rigidly mounted in the bore of said barrel, a spring-impelled, trigger-controlled impact plunger reciprocable within said barrel and in the rear of said impact block, a ball retainer rigidly mounted in the bore of said barrel between the free end of said barrel and said impact block and adjacent said impact block, a longitudinally reciprocable strike-pin mounted to slide longitudinally in said ball retainer and said impact block, and a light spring normally yieldingly holding said strike-pin in its rearmost position with its rear end projecting through said impact block into the path of the forward movement of said plunger.

13. In a toy gun, the combination of a frame, a barrel, an impact block rigidly mounted in the bore of said barrel, a spring-impelled, trigger-controlled impact plunger reciprocable within said barrel in the rear

of said impact block, the forward movement of which is limited by said impact block, a ball retainer fixedly positioned in said barrel adjacent and in front of said impact block, a longitudinally reciprocable strike-pin mounted to slide longitudinally in said ball retainer and in said impact block, and a light spring normally yieldingly holding said strike-pin in its rearmost position with its rear end projecting through said impact block into the path of the forward movement of said plunger, said ball retainer being provided with means to hold said ball in said retainer in alinement with the forward end of said strike-pin when said strike-pin is in its rearmost position.

14. In a toy gun, the combination of a frame, a barrel, an impact block rigidly mounted in the bore of said barrel, a spring-impelled, trigger-controlled impact plunger reciprocable within said barrel in the rear of said impact block, a propulsion spring operative to drive said plunger against said impact block, a ball retainer fixedly mounted within the bore of said barrel and forward of and adjacent to said impact block, a strike-pin mounted to reciprocate longitudinally in said ball retainer and impact block, and means for normally yieldingly holding said strike-pin in its rearmost position with its rear end projecting through said impact block into the path of the movement of said plunger, said ball retainer being provided with means to hold a plurality of balls within said barrel and normally in a row substantially parallel with the axis of said barrel, said ball retainer being provided with a passage at one end of said means to hold said plurality of balls terminating below the axis of said strike-pin whereby the ball at the end of said row may fall into a position in alinement with said strike-pin when said strike-pin is in its rearmost position.

15. In a toy gun, the combination of a barrel and a rigid frame provided with a slot through a side thereof extending parallel to the axis of said barrel, a stationary spring abutment in the upper part of said frame and in alinement with said barrel and having a longitudinal channel therein, an impact plunger mounted in said barrel and provided with a plunger rod having a straight portion extending rearwardly from said plunger substantially coaxially with the axis of said barrel into said channel and terminating in a portion extending at an angle to said portion and to a point outside of said channel from which point another portion of said rod extends outwardly through said slot in said frame, and a grip connected with said last mentioned portion for retracting said plunger.

16. In a toy gun, the combination with a barrel, an impact plunger reciprocable with-

in said barrel and an impact block rigidly mounted within said barrel to receive the impact of said plunger, of a projectile holder rigidly secured in said barrel in advance of said impact block and comprising a block provided with a longitudinal groove in the upper surface thereof to receive and support an alined series of balls and provided with a recess or channel at one end of said groove into which a ball at the end of said series may fall from said groove, a strike-pin extending longitudinally through said impact block and through said projectile holder below said longitudinal groove and reciprocable through said recess in said projectile holder, a light spring normally tending to hold said strike-pin in its rearmost position with the rear end of said strike-pin within the path of movement of said plunger and the forward end of said strike-pin substantially in the rear of said recess in said projectile holder.

In witness whereof, I have hereunto set my hand this 18th day of March, 1930.
